UNITED STATES PATENT OFFICE.

NORRIS ELMORE CLARK, OF PLAINVILLE, CONNECTICUT, ASSIGNOR TO ROBERT S. ALLYN, TRUSTEE, OF NEW YORK, N. Y.

EXPANDED-METAL MACHINE.

1,314,506.

Specification of Letters Patent.

Patented Sept. 2, 1919.

Application filed April 11, 1917. Serial No. 161,126.

To all whom it may concern:

Be it known that I, NORRIS ELMORE CLARK, a citizen of the United States of America, residing at Plainville, Connecticut, have invented a new and useful Expanded-Metal Machine, of which the following is a specification.

The invention is intended particularly as an attachment for a slitting press for taking stock which has been slitted or lanced by tools for instance such as shown in my Patent #1,146,554 and expanding it by a transverse corrugating action as claimed broadly in my Patent #1,052,888 and application #741376. The general principle of construction and mode of operation is similar to that of my Patent #1,146,553. Certain features of the method are covered by my Patent #1,224,877.

Briefly considered the invention contemplates longitudinal curved guides and feed rolls for the broad unslitted strips, longitudinal curved alternating guides and crimp rolls for the narrow unslitted strips between the broad unslitted strips. At least one roll of each pair of rolls is driven intermittently with the press so as to feed the stock and expand it simultaneously. All of the rolls and guides are carried by a vertically adjustable table so that their position can be varied with the height of the slitting tools. The alternate guides are preferably adjustable at one end with the crimp rolls which transversely corrugate the narrow un-slitted strips.

Figure 1, is a side view of mechanism embodying the improvements of my invention showing the housing, the gear and chain drive and their relation to the slitting tools.

Fig. 2, shows a fragment of slitted stock which is to be acted upon by the expanding mechanism.

Fig. 3, is a longitudinal vertical sectional view showing the expanding mechanism *per se* and its relation to the slitting tools.

Fig. 4, is a diagrammatic view showing the relative course of the un-slitted strips and rows of bonds.

Fig. 5, shows one pair of the rolls for feeding the broad un-slitted strips and in section shows the longitudinal guides on the plane of the line 5-5 of Fig. 3.

Fig. 6, is a transverse sectional view on the plane of the line 6-6 of Fig. 3.

Fig. 7, is a fragmentary view showing the adjustable support for the upper crimp roll and the alternate guides.

Figs. 8 and 9 are enlarged detail views of fragments of the crimp rolls or disks. 60

Fig. 10, is a side view showing the attachment for the press for supporting the roll and guide housings.

Fig. 11, is a vertical projection of the same at right angles to Fig. 6. 65

Fig. 12, is a plan view and section of the same on the plane of the line 12-12 of Fig. 10.

The press bed 11 supports the lower slitting die holder 12 carrying the cutters 13. 70 The upper or punch holder 14 carries the upper cutters 15 and is intermittently reciprocated by any suitable press mechanism so as to slit the stock as shown in Fig. 2, leaving broad unslitted strips 16-16, intermediate 75 narrow unslitted strips 17 and strands such as 18 and 19 connected together at intervals by bonds 20-20. The stock is fed intermittently by the introductory feed rolls 21, 21 which may be geared together in the 80 usual manner and driven for instance from the usual ratchet and gear, the latter being indicated by the pitch circle 22 which meshes with the gear on the shaft of the lower feed roll whose pitch circle is indicated at 23. The introductory feed rolls may form shallow beads such as 24 so as to facilitate the guiding and feeding of the stock through the slitting tools. 85

A curved guide bar 26 serves to support 90 each broad unslitted strip 16 as it comes from between the slitting tools. A curved cover guide 27 assists in holding a broad unslitted strip on the corresponding lower guide 26. The marginal guides may be provided with beads and grooves as shown at 28 in Fig. 6 for the beads 24 in the stock. Feed rolls are provided for moving the broad unslitted strips longitudinally of the guides 26 and 27. These feed rolls are preferably arranged in pairs having shafts 30, 31, 32 and 33 and feed disks such as 34 and 35, 36 and 37. The marginal disks may be beaded and grooved as shown at 38 in Fig. 5. Each guide preferably consists of two 105 longitudinal plates such as 39 with filler pieces such as 40 between them. The lower guides 26 extend from the upper faces of the die cutters clear through to the delivery end passing by the sides of the feed 110

disks 34 and 36. The fillers 40 of course are omitted at the feed disks. The cover guides 27 are constructed in a similar manner but extend only from the edge of the punch holder 14. The lower guides are carried by cross bars 41 41' and 42 and the upper guides are carried by cross bars 43 and 44.

The curved interior guides 46 extend from a line just in advance of and above the die cutters and between the pairs of broad strip guides and feed disks so as to direct the narrow unslotted strips 17 and thus in effect corrugate the slotted stock and form mesh-work as it is fed along as set forth in my former patents. The lower portion of each alternate guide is pivotally supported at 47 and its upper end is pivotally carried by a bracket 48 on a cross bar 49. An intermediate portion may be guided by a member 50. Although the expanding action is a natural and very gradual one as the stock is fed along, under certain circumstances there is a tendency of the inter-ribs or narrow slotted strips 17 to buckle. This I overcome by the employment of what may be termed crimping disks or rolls such as 51 and 52 on the shafts 53 and 54 respectively. These disks are provided with intermeshing teeth which form transverse corrugations in the inter-ribs after the expansion is completed and just before the stock is delivered. These teeth may be arched in cross section as shown in Fig. 9, so as to give a transverse arch to the corrugations formed in the inter-rib. The bearing 57 for the upper crimping roll shaft preferably has an extension arm 58 which carries the cross bar 49 so that the adjustment of the upper crimping rolls is accomplished simultaneously with the adjustment of the outer ends of the alternate guide members.

The housings for the shafts are preferably formed in two parts 60 and 61 secured together by bolts such as 62, 63, 64 and 65. The lower guides and rolls are all carried by the lower part 60 of the housing and the upper alternate guiding members and rolls are all carried by the upper part of the housing 61, the line of separation between the two parts of the housing being such as to permit all of the upper rolls and guides to be removed as a unit for the purpose of access to the lower parts and the stock in case of accident. As there is no occasion for adjusting the shafts 30 and 32 their bearings are fixed. The upper shafts 31 and 33 however, may be adjustable in the usual manner. As before mentioned the upper ends of the alternate members are adjustable so as to modify the expansion when desired and the upper crimping rolls are adjustable with them. The lower crimping rolls are also adjustable to 65 and from the upper crimping rolls so as to

permit variation in the transverse corrugating action.

As before mentioned the parts are particularly intended as an attachment for a press. The supporting member 66 is secured to the outer face by bolts such as 67 and provided with an extension 68 which rests on the press bed. A table 69 is guided by gibbs 70 and adapted to be clamped by bolts such as 71. The vertical part of the table is slotted at 72 to permit the table to be vertically adjusted, for instance, by means of a number of bolts such as 73 extending up through the flange 74 of the support so as to adjust the expanding mechanism to the height of the slitting dies. The housings 60 fit in grooves 75 in the table and are secured by bolts such as 76.

The driving may be effected by gears and disks as indicated by the dotted lines in Fig. 85 1. The support 66 carries a stud 77 for a gear whose pitch circle is indicated at 78 and which meshes with the main gear whose pitch circle is indicated at 22. A sprocket whose pitch circle is indicated at 79 is mounted on the stud with the gear whose pitch circle is indicated at 78 and a drive chain indicated at 80 transmits power to a sprocket on shaft 32 whose pitch circle is indicated at 81. This shaft also carries 90 sprockets whose pitch circles are indicated at 82 for chains indicated at 83 and at 84 for driving the shafts 53 and 30. The upper rolls may be driven from the lower rolls in the usual manner by gears such as shown at 100 85 and 86 in Fig. 5.

It will be obvious that the material expanded as herein set forth may be subsequently treated so as to form the broad unslotted strips into deep ribs either in a 105 separate machine or in a continuous process as shown in my Patent #1,224,877. I wish it also understood that the slitting press may be either a vertically acting press as shown in my Patent #1,224,523 or it may be inclined as set forth in my Patent #1,224,877.

I claim:—

1. In an expanded metal machine, the combination with a press and slitting cutters, of housings, feed disks and upwardly curved expanding guides carried by said housings and means for vertically adjusting the housings, disks and guides as a unit relative to said cutters.
2. In an expanded metal machine, a press attachment comprising a support, a table vertically adjustable thereon and feed disks and upwardly curved expanding guides carried by said table and adjustable therewith.
3. In an expanded metal machine, the combination with the slitting cutters of a stationary stud, a driving sprocket carried thereby, side housings, feed disks and upwardly curved expanding guides carried by said housings, said disks being driven from 13

said sprocket and means for vertically adjusting said disks and guides relative to said stud and sprocket.

4. In an expanded metal machine, the combination of slitting cutters with long curved expanding guides arranged in two sets, one set of said guides extending from adjacent the edge of the lower cutters and the other set of guides having bearing faces starting from a plane above said cutters and extending down between the guides of the other set and disks for feeding the stock along said guides.

5. In an expanded metal machine, the combination of two sets of stationary long curved expanding guides, the bearing faces of one set being arranged in one curved plane, the guides of the other set being arranged between the guides of the first set and having their bearing faces arranged in another curved plane substantially tangential to the first plane at the entrance end and in a plane substantially parallel to the first plane but spaced apart therefrom at the delivery end and means for feeding the partially slitted stock between the said guides.

6. In an expanded metal machine, the combination of two sets of stationary long curved expanding guides, the bearing faces of one set being arranged in one curved plane, the guides of the other set being arranged between the guides of the first set and having their bearing faces arranged in another curved plane substantially tangential to the first plane at the entrance end and in a plane substantially parallel to the first plane but spaced apart therefrom at the delivery end and means for crimping the narrow unslitted strips of the stock as they leave the ends of the intermediate guides.

7. In an expanded metal machine, the combination of two sets of stationary long curved expanding guides, the bearing faces of one set being arranged in one curved plane, the guides of the other set being arranged between the guides of the first set and having their bearing faces arranged in another curved plane substantially tangential to the first plane at the entrance end and in a plane substantially parallel to the first plane but spaced apart therefrom at the delivery end, means for feeding the partially slitted stock between the said guides, feed disks arranged to move the unslitted strips of the fabric along the curved guides of the first set and feed disks for drawing the intermediate strips along the curved guides of the other set.

8. In an expanded metal machine, two sets of long curved expanding guides arranged in substantially one plane at one end and having alternate guides with their bearing faces in a plane spaced apart from each other at the other end, and crimp

rolls having their bearing faces in line with the bearing faces of the intermediate guides.

9. In an expanded metal machine, two sets of long curved expanding guides arranged in substantially one plane at one end and having alternate guides with their bearing faces in a plane spaced apart from each other at the other end, crimp rolls having their bearing faces in line with the bearing faces of the intermediate guides and means for simultaneously adjusting the crimp rolls and the intermediate guides connected therewith.

10. In an expanded metal machine, two sets of long curved expanding guides, transverse shafts, crimp rolls carried by said shafts at the ends of the alternate guides, supports for the ends of the intermediate guides carried by said shafts and adjustable therewith.

11. In an expanded metal machine, two sets of long upwardly curved expanding guides, the guides of one set being formed of two side bars and feed disks arranged between said side bars for moving the unslitted strips along said side bars.

12. In an expanded metal machine, housings formed in two parts, longitudinally extending curved guide bars carried by the lower parts of said housings, longitudinally extending curved guide bars alternating with the other guide bars and carried by the upper parts of said housings, upper and lower sets of feed disks carried respectively by the upper and lower parts of the housings and means for detachably securing the upper and lower parts of the housings together.

13. In an expanded metal machine, longitudinally extending curved upper and lower rib guides, upper and lower feed disks for feeding rib stock along said guides, longitudinally curved intermediate guides, housings for supporting said members, said housings being formed in two parts, the lower parts carrying all of the lower guides and disks and the upper parts carrying all of the upper guides and disks and means for detachably securing said upper parts to said lower parts.

14. In an expanded metal machine, curved guides for the rib stock, curved guides alternating therewith and having their bearing surfaces in substantially the same plane with the bearing faces of the first mentioned guides at the entrance end and in a plane spaced apart therefrom at the delivery end and crimp rolls in line with the delivery ends of said intermediate guides.

15. In an expanded metal machine, curved guides for the rib stock, curved guides alternating therewith and having their bearing surfaces in substantially the same plane with the bearing faces of the first mentioned guides at the entrance end and in a plane spaced apart therefrom at the delivery end,

- crimble rolls in line with the delivery ends of said intermediate guides and means for simultaneously adjusting said intermediate guides and said crimble rolls.
- 5 16. In an expanded metal machine, a set of relatively stationary long curved guides for the rib stock of a partially slitted sheet, long curved guides alternating therewith, means for pivotally supporting said latter 10 guides at one end and means for adjusting the opposite ends of said latter guides between the first mentioned guides.
- 15 17. In an expanded metal machine, two pairs of sets of feed disks, long curved rib guides extending between said disks and long curved guides alternating with said first mentioned curved guides and having their opposite ends extending beyond said feed disks, the bearing faces of all of said 20 guides being in a closely adjacent plane at the entrance end and the bearing faces of the two sets of guides being in planes spaced apart from each other at the delivery ends.
- 25 18. In an expanded metal machine, the combination of slitting cutters together with means for feeding the stock to said cutters, upper and lower sets of spaced disks for feeding the marginal and interior unslotted strips in a plane above said cutters 30 and away therefrom and upwardly curved guides leading therefrom arranged in two sets, the bearing faces of the two sets being in planes spaced apart from each other at the delivery end.
- 35 19. In an expanded metal machine, two sets of curved expanding guides and crimble rolls having their bearing faces arranged in line with the delivery end of the guides of one set, said crimble rolls having transverse arched crimble teeth. 40
20. In an expanded metal machine, the combination with slitting cutters arranged to slit portions of a sheet and leave marginal and intermediate unslotted strips, long guides curving out of the plane of the 45 cutters for guiding the unslotted strips along a curved plane, a plurality of pairs of feed disks arranged at intervals along each curved guide for engaging the unslotted strips of the stock and curved expanding members between the curved guides. 50
21. In an expanded metal machine, the combination with cutters for slitting portions of the stock and leaving marginal and intermediate unslotted strips of upwardly 55 curving guides for directing the unslotted strips upward out of the plane of the cutters, means for engaging the unslotted strips to feed the stock upwardly along said guides and upwardly curved expanding members 60 arranged between said guides for opening the meshwork.
22. In an expanded metal machine, the combination of upper and lower cutters for slitting sections of the stock and leaving unslotted strips spaced apart, of an attachment for expanding the slitted portions of the stock comprising, curved guides for the unslotted strips with their bearing faces arranged to direct the unslotted strips in a 65 curved plane, means for feeding the stock, and curved expanding members arranged between the curved guides. 70

NORRIS ELMORE CLARK.
